(57) **CLAIM**

The ornamental design for a photovoltaic sculpture, as shown and described.

DESCRIPTION

FIG. 1 is a front-top perspective view of the photovoltaic sculpture of the present invention, with the solar panels facing forward and upward.

FIG. 2 is a front perspective view of the sculpture.

FIG. 3 is a rear perspective view of the sculpture, showing the rear faces of the solar panels.

FIG. 4 is a left side view of the sculpture.

FIG. 5 is a right side view of the sculpture; and,

FIG. 6 is a top plan view of the sculpture.

1 Claim, 6 Drawing Sheets

FIG. 1.

FIG. 2.

FIG. 3.

FIG. 4.

FIG. 5.

FIG. 6.
